Inventor—

Alfred Jones

by George F. Folkes, his Attorney

UNITED STATES PATENT OFFICE.

ALFRED JONES, OF BIRMINGHAM, ENGLAND.

PRESS GUARD.

Application filed June 12, 1924. Serial No. 719,630.

To all whom it may concern:

Be it known that ALFRED JONES, a subject of the King of Great Britain, residing at 15 Oxford Street, Birmingham, England, has invented a new and useful Improvement in or Connected with Press Guards; and he does hereby declare the following to be a full, clear, and exact description of the same.

This invention has reference to improvements in and connected with press guards for clutch controlled power presses and other machinery of a similar character, and has for its object to provide an effective but simple form of press guard which avoids any possibility of damage to the hands of the operator or feeder to the press, the guard being readily adapted to and connected with power presses or other machines of this character without involving any material alteration in the construction thereof.

The invention consists of the combination with a clutch controlled power press or machine of a like character of a guard which is characterized by the guard plate being independent of the mechanism for operating the press, the guard being adapted for traversable motion across the front of the press by the operator, the guard plate constituting a stop or bar to a mechanism connected to the treadle or hand lever of the press when it is in any position other than that which the guard plate occupies when it has been completely traversed across the front of the press. The invention further resides in the provision of a spring controlled member associated with the said guard plate in such a manner that should the ram or plunger of the press descend before the guard plate has been traversed completely across the front of the press the said spring controlled member is released by the downward motion of the ram or plunger and the guard plate is caused to travel rapidly across the front of the press and forcibly remove the operator's hand from the danger zone.

The invention will now be described with particular reference to the accompanying sheet of drawings, wherein:

Fig. 1 is a front elevation of a press guard constructed in accordance with the invention as applied to a power press, the guard being shown in the open or retracted position.

Fig. 2 is a similar view to Figure 1 showing the guard in the closed or projected position.

Fig. 3 is a plan of the press guard as seen in Figure 2.

Fig. 4 is an elevation to an enlarged scale of the automatic safety release device, and

Fig. 5 is a plan of part of Figure 4.

The guard plate which comprises a metal framework 6 having a wire mesh panel 7 is slidably mounted by means of its extending angle section upper side 6^a within guide slots 8^b formed in a member 8^a secured to brackets 8 attached to the frame 9 of the press, a handle 10 secured to the member 6^a affording a convenient means for effecting the traverse of the guard plate.

The lowering or raising of the plunger 11 onto or away from the work contained in the die 12 is effected by means of a lever 13 pivotally mounted on an ear 9^a of the press frame 9 the lever 13 having a pin and slot connection with a rod 14 operating the clutch mechanism. Secured to the lever 13 is a downwardly depending cranked section 13^a the lower end of which when the guard is in the open or retracted position, see Figure 1, contacts with the upper surface of the side 6^a of the guard plate whereby the said lever 13 is locked against operation when the guard plate is in the aforesaid position.

Attached to and moving with the plunger 11 is a cranked rod 15 the lower end of which is adapted under circumstances to be herein-after described to co-operate with a cam shaped lever 16 pivotally secured to an arm 17 in turn pivotally mounted on the member 8^a by means of a stud 18 the pivotal motions of the lever 16 and arm 17 taking place in planes at right angles to one another. Slidably mounted at the front of the press is a square rod 19 adapted to be controlled by a coil spring 20, the rod 19 passing through the vertical sides of the guard plate and the rod head 19^a being adapted to abut one side of the guard plate when the plate is in its open position as is seen in Figure 1. The other end of the rod 19 is disposed within a square slot 8^c formed in the member 8^a the end of the said rod normally abutting the arm 17 whereby the rod is maintained in its out of action position and the spring 20 under tension. A spring 21 secured to the arm 17 and to a finger 8^d secured to the bracket 8 normally maintains the arm 17 in its aforementioned locking position.

Mounted on the extending top side 6^a of the guard plate is a projection 22 adapted to contact with the cam lever 16 and to rock

this lever about its pivot and thereby remove it out of the path of the cranked rod 15 during the normal working of the press, a spring 23 secured to the lever 16 and to the member 8^a returning the lever 16 to its acting position upon the removal of the projection 22.

The operation of the guard is as follows: When the guard plate is in the open or 10 retracted position and access to the press is permissible, the lower end of the cranked extension 13^a of the lever 13 contacts with the upper surface of the top side 6^a and thereby renders the actuation of the lever 15 13 to effect a lowering of the plunger impossible as has hereinbefore been mentioned. Upon the operator desiring to work the press the guard plate is traversed along the face of the press until the whole of the side 20 6^a has been removed from contact with the cranked extension 13^a of the lever 13 in which condition access to the press is prevented and the operation of the lever 13 permitted. It should be noted that this arrangement ensures that the press guard must be 25 in its fully closed position before the lever 13 can be operated and the descent of the plunger 11 effected.

In the event of the clutch mechanism 30 seizing while the guard is in the open position and the consequent descent of the plunger, the cranked rod 15 strikes the lever 16 and rocks the lever 16 and the arm 17 about the stud 18, thereby freeing the slot 35 8^c from the obstruction of the arm 17, whereupon the rod 19 under the action of the spring 20 shoots across the face of the press and carries with it the press guard and thereby forcibly removes the hands of the 40 operator from the danger zone. The rod 19 is reset by any convenient means for the subsequent operation of the press, but in order to prevent the release of the safety device during the normal working of the 45 press it is arranged that on the traverse of the guard plate to the closed position the projection 22 thereon moves the lever 16 out of the path of the cranked rod 15 and thereby prevents the release of the rod 19. 50 It will thus be observed that a press guard in accordance with this invention secures complete protection for the operator since in normal working the press cannot be operated until the guard is in its completely 55 closed position, and should the mechanism foul through any cause and accidentally set the press in operation the safety device ensures that the operator's hands are removed from the press before the plunger descends 60 on to the lower die.

Claims:—

1. In a power press, the combination of a lever for controlling the operation of the press, and a member adapted to be traversed 65 across the front of the press to prevent ac-

cess thereto, said member having a section thereof so disposed within the path of the actuating lever that the operation of the said lever is prevented unless the member is in its completely traversed position. 70

2. In a power press the combination of a lever for controlling the operation of the press, a member adapted to be traversed across the front of the press to prevent access thereto and so related to said lever that the lever cannot be operated unless said member is in its fully closed position, and means for freeing the front of the press from obstructions in the event of the accidental operation thereof due to mechanical derangement. 75 80

3. In combination with a power press having a frame, a plunger mounted in said frame and a fixed die; a lever for controlling the operation of said plunger, a guard adapted to be traversed across the front of the press to prevent access thereto said guard co-operating with said lever so that the lever cannot be operated unless the guard is in its fully closed position, means controlled by the plunger for forcibly removing the hands of the operator in the event of the accidental operation of the press, and means for rendering inactive the first mentioned means when the guard is in 90 its closed position. 95

4. In combination with a power press having a frame, a plunger mounted in said frame and a fixed die; brackets secured to said frame, a guide member secured to said 100 brackets, a guard plate having one side thereof slidably mounted in said member, means for traversing said guard plate across the front of the press to prevent access thereto, a lever for controlling the operation of said plunger and co-operating with said plate whereby the lever cannot be operated unless the said plate is in its fully closed position, means controlled by said plunger for forcibly removing the hands of the operator in the event of the accidental operation of the press due to mechanical derangement, 105 and means for rendering inactive the first mentioned means when the guard plate is 110 in its fully closed position. 115

5. In combination with a power press having a frame, a plunger mounted in said frame, and a fixed die; brackets secured to said frame, a slotted plate secured to said brackets, a guard plate having an extending side thereof slidably mounted in the slotted plate, a handle for traversing said guard plate across the front of the press to prevent access thereto, a lever for controlling the operation of the plunger and co-operating with the guard plate whereby the lever cannot be operated unless the guard plate is in its fully closed position, a cranked rod connected to said plunger, an arm pivoted to said slotted plate, a cam shaped lever 120 125 130

pivotaly mounted on said arm and having one end thereof disposed in the path of said rod, and a spring controlled rod slidably mounted within said slotted plate and controlled by said cam-shaped lever said rod being adapted to traverse the guard plate rapidly across the front of the press in the event of any operation thereof due to mechanical derangement and thereby to free

10 the front of the press.

6. In combination with a power press having a frame, a plunger mounted in said frame, and a fixed die; brackets secured to said frame, a slotted plate secured to said 15 brackets, a guard plate having an extending side thereof slidably mounted in the slotted plate, a handle for traversing said guard plate across the front of the press and thereby preventing access thereto, a lever for controlling the operation of said plunger 20 and co-operating with the guard plate where-

by the lever cannot be operated unless the said guard plate is in its fully closed position, a cranked rod connected to said plunger, a spring controlled arm pivotaly 25 mounted on said slotted plate, a cam shaped lever pivotally mounted on said arm and having one end thereof disposed in the path of said rod, a spring controlled rod slidably mounted in said slotted plate and controlled 30 by said arm said rod being adapted to traverse the guard plate rapidly across the front of the press in the event of the accidental operation thereof, and a projection secured to the guard plate and adapted to 35 remove the cam shaped lever from the downward path of the cranked rod when the guard plate is in its fully closed position.

In testimony whereof, I have signed my name to this specification.

ALFRED JONES.
